Patented Sept. 13, 1921.
2 SHEETS—SHEET 2.

UNITED STATES PATENT OFFICE.

JOHN MALIN ARTHUR, OF NEW WOODSTOCK, NEW YORK, ASSIGNOR OF ONE-HALF TO
JAMES W. ARTHUR, OF AKRON, OHIO.

RUBBER-SHOE-VULCANIZING MACHINE.

1,390,478.

Specification of Letters Patent. Patented Sept. 13, 1921.

Application filed March 2, 1921. Serial No. 448,975.

To all whom it may concern:

Be it known that I, JOHN M. ARTHUR, a citizen of the United States, residing at New Woodstock, in the county of Madison 5 and State of New York, have invented certain new and useful Improvements in Rubber-Shoe-Vulcanizing Machines; and I do declare the following to be a full, clear, and exact description of the invention, such 10 as will enable others skilled in the art to which it appertains to make and use the same.

This invention relates to an improved vulcanizing machine for use in connection 15 with rubber shoes and boots, and one object of the invention is to provide an improved outfit of the character described including an improved shoe or boot holding or supporting pedestal and also an improved clamp holding device so constructed that a steam box may be clamped into tight engagement with the sole portion of a shoe or a pressure band drawn upwardly to hold 20 a patch in tight engagement with the top portion of a boot placed upon the pedestal.

Another object of the invention is to so construct the clamp holding ring that the clamp may be set at the desired angle transversely of the boot and further so constructed that the holder may be swung longitudinally of the boot and secured in the set position.

Another object of the invention is to so construct the device that it may be supported from a wall where it will take up a small amount of room.

Another object of the invention is to provide a device of the character described which will be easy to operate and further 40 so constructed that the main portion of the heat from the pedestal or last, as it may be termed, will be confined to that portion of the rubber shoe or boot which it is desired to repair.

45 This invention is illustrated in the accompanying drawings, wherein:

Figure 1 is a view showing the improved device in front elevation.

Fig. 2 is a view showing the sole and 50 upper repair element of the outfit partially in vertical section and partially in side elevation.

Fig. 3 is a view showing the heel repair element of the device in side elevation.

55 Fig. 4 is a fragmentary view in front ele-

vation showing the manner of holding a patch on the side portion of the upper portion of a boot.

Fig. 5 is a vertical sectional view taken along the line 5—5 of Fig. 2.

Fig. 6 is a perspective view of the ring carrying the clamp of Figs. 4 and 5.

This improved outfit is for use in connection with rubber shoes and boots for applying soles and heels and for applying patches to the rubber shoes or boots and is provided with a steam pipe 1 provided with couplings 2 and 3 at its ends and with a coupling 4 intermediate its length, the coupling 4 being provided with an inlet intermediate its length and normally closed by a removable plug 5 so that if desired, a steam boiler or line, not shown, may be connected with the inlet of the coupling 4 when the plug 5 is removed. The couplings 2 and 3 will also be open at their lower ends and provided with removable closures so that if desired, a steam line 6 may be connected with one of these couplings for supplying steam from a suitable source of supply. Pedestals 7 and 8 which are hollow are connected with the upper ends of the couplings 2 and 3 and are suitably shaped as shown in Figs. 2 and 3 for fitting into a rubber shoe or boot 9, the pedestal 7 having its upper end portion formed into a flat and relatively short head 10 for fitting into the heel portion of the boot and the pedestal 8 having its upper end portion formed into an elongated head 11 for fitting into the toe portion of the boot. When applying a sole or making repairs to the sole of a boot, a steam box 12 of the proper size is made use of, this steam box having a handle 13 and having an inlet carrying a nipple 14 so that a flexible steam pipe 15 may be connected with the steam box 12. This steam pipe 15 is connected with the valve 15' and it will be readily seen that when it is desired to use the steam box 12, it is simply necessary to open the valve and steam will pass 70 from the coupling 4 through the valve 16 and pipe 15 into the steam box.

Brackets 16 and 17 are connected with the supporting board 18 which will be secured to the wall by suitable fasteners and these brackets are provided with clamping plates 16' and 17' so that the pedestals 7 and 8 may be firmly gripped and thus the pedestals held in an operative position. The 75 80 85 90 95 100 105 110

bracket 16 has its forward end portion extended upwardly to provide a post 19 having a bearing head 19' at its upper end and the bracket 17 has its end portion extended 5 upwardly to provide a binding post 20. The clamp supporting ring 21 shown in Fig. 6 will be connected with the bearing head 19' of the arm 19 by means of a releasable pivot bolt which passes through the head 19' 10 and arms 23 of the ring. It will thus be seen that by releasing the bolt 22 the ring may be tilted to the desired position and releasably but securely held in this position by tightening the bolt. This ring is provided 15 with a slot 24 which extends circumferentially of the ring and is adapted to receive the threaded stem 25 of the clamp as shown in Fig. 5. A bearing 26 is provided for this threaded stem 25 and a 20 washer 27 and lock-nut 28 have been mounted upon the stem above the ring 21 so that the stem may be secured in a set position after the clamp has been tightened. It should be noted that the stem is provided at 25 its lower end with a substantially spherical head 29 which fits into a socket 30 carried by the steam box 12 and further that a plate 31 which carries hooks 32 is loosely mounted upon the stem and rests upon the 30 head 29.

In connection with the pedestal 7, there has been provided a yoke 33 having a bearing in its cross-head through which passes the stem 34 of a clamp as shown in Figs 1 35 and 3. This clamp is provided with a plate 35 having a swivel connection with the stem and this plate is adapted to engage the heel 40 of the boot when the heel is being vulcanized in place. This yoke 33 straddles the pedestal and is pivotally mounted by pivot screws 36 which fit into suitable threaded openings 45 formed in the bracket 17 and clamping plate 17'. It will thus be seen that this machine is so constructed that the yoke 33 as well as the ring 21 may be tilted to a desired position and securely held in the adjusted position. It will be further noted that the heel or sole may be firmly held in place while the vulcanizing is being accomplished as shown 50 in Figs. 1, 2, and 3.

When this improved device is in use, it is set up as shown and the source of steam supply connected either with the inlet of the coupling 4 or with one of the couplings 2 or 55 3. If a heel is to be vulcanized in place, the rubber boot will be put in place as indicated in Fig. 3 with the heel put in place and clamped down in tight engagement with the boot by rotating the stem 34 to bring the plate 35 into tight engagement with the heel. The pedestal 7 is heated by the steam and the vulcanizing will be accomplished. If it is desired to have the boot drawn forwardly to prevent any danger of it slipping 60 rearwardly, a strip similar to a strip of

bandage may be placed about the boot and upstanding arm 20 and thus the boot will be prevented from having any tendency whatever toward moving rearwardly.

If a sole is to be vulcanized upon the toe portion of the boot, the boot will be put in place as shown in Fig. 2 with the extended head of the pedestal 8 extending up into the toe portion of the boot. A steam box 12 of the proper size will be put in place and 70 tightly clamped by turning the stem 25 to bring the spherical head 29 into engagement with the socket 30. The valve 16 will then be opened to admit steam to the steam box 12 and the vulcanizing will thus be easily 75 and quickly accomplished. If a patch is to be applied to the side or upper of the toe portion of the boot, the boot will be put in place as shown in Fig. 2 but in using the steam box, a strip 37 which is preferably 80 formed of heavy fabric but which may be formed of any suitable material is passed about the toe portion of the boot as shown in Fig. 4 with its end portions engaged by the hooks 32 of the plate 31. The stem 25 85 can then be turned so that it will move outwardly and thus apply pressure which will hold the patch in place. It is of course understood that when the apparatus is in use, the yoke 33 or the ring 21 will be set at 90 the proper angle and secured by tightening of the bolt 22 or screws 36.

A structure has thus been provided by means of which soles, heels and patches can be easily and quickly applied to rubber shoes 100 or boots and vulcanized into place.

I claim:

1. A shoe vulcanizing outfit comprising a hollow steam heated pedestal, a support for said pedestal, a carrier pivotally connected 105 with said support and extending about the upper portion of said pedestal and having movement longitudinally of the upper portion of the pedestal, and clamping means adjustably carried by said carrier for movement transversely of the upper portion of said pedestal, and at right angles to the movement of said carrier when the carrier is adjusted.

2. A shoe vulcanizing outfit comprising a 110 heated pedestal, a support, a carrier ring pivotally connected with said support for swinging movement longitudinally of the sole portion of a shoe placed upon said pedestal, the ring being provided with a slot extending a greater portion of its circumference, and a clamp carried by said ring in the slot and adjustable circumferentially of said ring for movement transversely of the sole portion of a shoe carried by said pedestal 115 from one side of the shoe to the opposite side.

3. A vulcanizing outfit comprising a steam pipe, a hollow pedestal carried by and communicating with said steam pipe, a support, 120

- a carrier carried by said support, a clamp carried by said carrier and including a stem adjustably mounted for longitudinal movement, a steam box for engaging a shoe placed upon said pedestal, means for conducting steam from said steam pipe to said steam box, the steam box having a socket for receiving the end of the stem of said clamp when the clamp is brought into engagement with said steam box, and an element loosely mounted upon said stem and at its ends provided with means for engaging a pressure strip for engaging a shoe placed upon said pedestal.
- 15 4. A shoe vulcanizing outfit comprising a steam pipe, a hollow pedestal carried by and in communication with said steam pipe, a wall engaging support including a pedestal engaging clamp and having an upturned forward end portion, a circular ring pivotally connected with the upturned forward
- portion for swinging movement over the pedestal longitudinally of the sole portion of a shoe upon the pedestal, the ring having a circumferentially extending slot for the greater portion of its periphery, an internally threaded bearing slidable circumferentially of the ring and fitting against the inner face of the ring and extending into the slot, a washer plate engaging the outer face of the ring, and a clamp including a threaded stem passing through the socket radially of the ring and a locking nut upon the stem for engaging the washer plate and securing the clamp and bearing in a set position.
- 20 In testimony whereof I have hereunto set my hand.

JOHN MALIN ARTHUR.
